FLARING TOOL

Anton J. Janik and William A. Lauck, Elyria, Ohio,
assignors to The Ridge Tool Company, Elyria, Ohio,
a corporation of Ohio

Filed Mar. 1, 1963, Ser. No. 73,775

Term of patent 14 years

(Cl. D54—13)

Fig. 3

Fig. 4

Fig. 5

Fig. 6

FIG. 1 is a side elevational view of the flaring tool embodying our new design;

FIG. 2 is a side elevational view at 90° to that of FIG. 1;

FIG. 3 is a side elevational view at 180° to that of FIG. 1;

FIG. 4 is a side elevational view at 180° to that of FIG. 2;

FIG. 5 is a top plan view with a portion of the handle broken away; and

FIG. 6 is a bottom plan view thereof.

The characteristic features of our design reside in the specific configuration of the yoke and drive collar unit as shown.

We claim:

The ornamental design for a flaring tool, as shown and described.
